Primary Examiner — Patricia Palasik*(74) Attorney, Agent, or Firm* — Wilson Sonsini Goodrich & Rosati(57) **CLAIM**

The ornamental design for a personal robot, as shown and described.

DESCRIPTION

FIG. 1 is a perspective view of the personal robot showing an embodiment of our new design;

FIG. 2 is a bottom view thereof;

FIG. 3 is a top view thereof;

FIG. 4 is a front view thereof;

FIG. 5 is a rear view thereof;

FIG. 6 is a right side view thereof; and,

FIG. 7 is a left side view thereof.

The broken lines in FIGS. 1-7 are for illustrative purposes only and form no part of the claimed design.

1 Claim, 7 Drawing Sheets---
